(57) **CLAIM**

The ornamental design for a deer feeder, as shown and described.

DESCRIPTION

FIG. 1 is a perspective view of the deer feeder showing its intended use strapped to a tree in the native environment of deer.

FIG. 2 is a perspective view of the deer feeder.

FIG. 3 is a side view of the deer feeder.

FIG. 4 is a front view of the deer feeder.

FIG. 5 is a back view of the deer feeder.

FIG. 6 is a top view of the deer feeder; and,

FIG. 7 is a bottom view of the deer feeder.

The broken lines showing the outline of hooks, straps, and the native environment for deer in FIG. 1 are for illustrative purposes only and form no part of the claimed design.

1 Claim, 7 Drawing Sheets---
